UNITED STATES PATENT OFFICE.

WILLIAM BOWDEN, OF McHENRY, MISSISSIPPI.

WRENCH.

1,014,563.

Specification of Letters Patent.

Patented Jan. 9, 1912.

Application filed December 12, 1910. Serial No. 596,801.

To all whom it may concern:

Be it known that I, WILLIAM BOWDEN, a citizen of the United States, residing at McHenry, in the county of Harrison and State of Mississippi, have invented a new and useful Wrench, of which the following is a specification.

It is the object of this invention to provide a wrench having a movable jaw which may be held by novel means, in various adjusted positions with respect to the fixed jaw.

Another object of the invention is to provide a movable jaw of novel and improved form, having means for adjustable connection with the handle of the wrench.

In the drawings, Figure 1 is a side elevation showing the movable jaw locked in place upon the handle of the wrench, parts being broken away; Fig. 2 is a side elevation showing the movable jaw tiltably united with the handle of the wrench, and in the position which it will assume while gripping an article; the form of the invention shown in Fig. 2 being modified slightly from the showing of Fig. 1; Fig. 3 is a transverse section upon the line 3—3 of Fig. 1.

The handle of the wrench is denoted by the numeral 3, the handle being supplied with an angularly disposed fixed jaw 1, having teeth 2 upon its inner face. A movable jaw 6 is slidable upon the handle 3, so as to coöperate with the fixed jaw 1, the end 9 of the movable jaw 6 being provided with teeth 10, coöperating with the teeth 2 of the fixed jaw 1.

Speaking generally, the movable jaw 6 is a U-shaped structure including arms 11 connected by a head 15. The handle 3 is disposed between the arms 11, the head 15 being disposed upon one side of the handle 3 and a filler 12 being disposed between the arms 11 upon the other side of the handle 3. The filler 12 is maintained in place between the arms 11 by means of screws 13 or other retaining elements adapted to a like end.

The invention further includes a nose 5, supplied with a shank 8, adapted to register in a recess 7 in one end of the filler 12, the nose 5 being held in place upon the filler 12 in any desired manner. The nose 5 is adapted to engage with teeth 4 formed in one edge of the handle 3. The nose is fashioned from steel or other hard metal, and may be removed from the filler 12 and

replaced by another nose when worn or injured. The edge of the filler 12 which is disposed toward the handle 3 is concaved, as at 14, thus reducing the sliding friction 69 between the movable jaw 6 and the handle 3.

Positioned between the handle 3 and the head 15 of the movable jaw, is a spring plate 17 secured at one end to the head 15 by means of a bolt 16 or other fastening device. 65 Adjacent its free end the spring 17 is curved, as shown at 18, to bear against the edge of the handle 3. The spring 17 acts to maintain the nose 5 in engagement with the teeth 4, the movable jaw 6, however, being tiltable upon the handle 3 so as to withdraw the nose 5 from the teeth of the handle. To facilitate this tilting of the movable jaw 6, the same is provided as with an outstanding lug 21, the face of which is 75 serrated as shown at 22. The thumb or finger of the operator may be placed upon this serrated lug in order to tilt the movable jaw.

The invention further includes a movable member, preferably a thumb screw 19, 80 threaded through the head 15 of the movable jaw, and adapted to engage one edge of the handle 3, this thumb screw 19 being equipped with a locking device, preferably lock nut 20, whereby the thumb screw may 85 be held against rotation in the movable jaw.

In the modified form of the invention shown in Fig. 2, the movable jaw 60 is equipped with a filler 120, the nose 50 being formed integrally with the filler, instead of 90 being removable therefrom, as in Fig. 1.

When the thumb or finger of the operator is placed upon the lug 21, the movable jaw 6 may be slid transversely of the handle 3, withdrawing the nose 5 from the teeth 4, 95 whereupon the movable jaw may be slid longitudinally of the handle 3, into adjusted positions with respect to the fixed jaw 1. When the movable jaw is released, the spring 17, engaging the handle 3, will bring 101 the nose 5 in engagement with the teeth 4. When the wrench is applied to an article, to rotate the same the movable jaw 6 will tilt slightly, as shown in Fig. 2, the nose, however, remaining in engagement with 105 the teeth 4.

When it is desired to hold the movable jaw in fixed relation with respect to the other jaw of the wrench, the thumb screw 19 may be rotated as shown in Fig. 1, the 110 thumb screw engaging the shank 3 and binding the movable jaw 6 firmly upon the

handle of the wrench, the lock nut 20 being rotated until it engages the movable jaw.

Referring to Figs. 1 and 2, it will be seen that the teeth 4 of the handle 3 terminate at such a distance from the fixed jaw 1, that when the element 5 in the one instance, and the element 50 in the other instance, are engaged with the teeth 4, the opposite end of the filler will bear upon a plane surface in the handle 3, located between the teeth 4 and the fixed jaw 1.

What I claim is:

A wrench comprising a handle provided with a fixed jaw; a movable jaw including an arched member inclosing the handle slidably, and a filler held within the arched member, that edge of the filler which is adjacent the handle being concaved, whereby the filler will bear against the handle adjacent the ends of the filler only; there being teeth in the handle, adapted to be engaged by one end of the filler only, the teeth ter-

minating at such a distance from the fixed jaw, that when one end of the filler is engaged with any of the teeth, the other end of the filler will bear upon a plane portion of the handle lying between the fixed jaw and the teeth; there being a spring in the movable jaw, normally holding both ends of the filler in engagement with the respective parts of the handle; a movable member in the movable jaw, independent of the spring, and adapted to engage the handle to hold both ends of the filler against the handle; and means for holding the movable member in a handle-engaging position.

In testimony that I claim the foregoing as my own, I have hereto affixed my signature in the presence of two witnesses.

WILLIAM BOWDEN.
